(57) **CLAIM**

The ornamental design for a windshield wiper cover, as shown and described.

DESCRIPTION

FIG. 1 is a top perspective view of the windshield wiper cover. FIG. 2 is a front view of the windshield wiper cover.

FIG. 3 is a front view of the central portion of the windshield wiper cover.

FIG. 4 is a top view of the central portion of the windshield wiper cover.

FIG. 5 is a perspective top view of the central portion of the windshield wiper cover; and,

FIG. 6 is a perspective bottom view of the windshield wiper cover.
